AUTOMATIC DENSITY CONTROL FOR
CLASSIFIERS

Cooper Shapley, Jr., Salida, Colo.

Application January 4, 1944, Serial No. 516,984

16 Claims. (Cl. 209—491)

This invention relates to improvements in wet material classifiers, and more specifically to automatic pulp density control means for the discharge of a constant density pulp from the classifier by means of a floating baffle. In any wet classifier apparatus, the top film of pulp overflowing the weir is very dilute and of low density, while a few inches below the surface the pulp is much more dense and of a higher specific gravity.

Classifiers on which this improvement is applicable are generally of the rake or spiral type and usually comprise elongated tanks into which is constantly admitted material which has been ground in admixture with water by a ball mill to provide the desired pulp. This pulp is delivered to such a tank by means of a launder interconnecting the tank and mill, and includes certain recovered material which is constantly being returned to the ball mill for regrinding by means of another launder interconnecting same. The process is thus continuous with a constant recovery of the properly sized material as finished product. Generally, this pulp, consisting of ground material and water, is admitted near the lower end of the tank and permitted to flow or spill over that end with a consequent continuous separation of the properly sized particles as a finished product.

While the material is ground in the ball mill to a predetermined maximum coarseness, the ground material as a whole will comprise variable sized particles ranging from that of the maximum coarse grind to very much smaller particles.

It is to be particularly noted at this point, that the material comprising the pulp is thus variable, comprising particles of substantially different specific gravity and that many of the larger particles of this pulp may be much lighter than smaller particles which are more valuable and which it is desired to eventually recover in the flotation process.

The object sought in the use of present classifiers is therefore to separate the lighter particles which will remain in suspension longer and will be carried up and spilled over the discharge end or weir of the tank, while the heavier particles settle to the bottom and are recovered from the tank by mechanical means, such as a rake or other conveyor and returned to a ball mill for regrinding, for use in subsequent pulp in the classifier tank as above explained.

With the classifiers or separators now in use, mechanical adjustments are relied upon for controlling the separation of particles of given

specific gravity, such as by increasing or decreasing the speed of the mechanism, increasing or decreasing the density of the pulp, changing the inclination of the tank bottom, and/or changing the distance between the bottom of the tank and rakes or other conveyor means. While such adjustments obviously alter the weight of the separated particles, generally, they are far from being critical and necessitate time and labor to operate and adjust each time it may be desirable to regulate the pulp density or keep it uniform.

With the above general construction in view, the primary object of the invention is the provision of means for maintaining the pulp which flows or spills over the weir at the discharge end of the tank, at a substantially constant density or specific gravity.

A further object of my invention is the provision of a classifier tank having a baffle which is constructed and arranged to float in the pulp adjacent the discharge end of the tank, the baffle being adapted to rise and fall automatically in the tank according to changes in density of the pulp at the lower edge of the baffle so as to cause dilute surface pulp to pass under the lower edge of the baffle and thus help to carry over the weir, the denser and higher specific gravity material found at the desired depth below the surface of the classifier pulp.

A further object of the present invention is to remove from the classifier and cause to be carried over the weir, a certain portion of the worthless gangue as coarse material, thus relieving the classifier and grinding apparatus of further handling this material.

A still further object of my invention is the provision of such an automatic baffle for uniformly controlling the density of the pulp at the overflow end of the tank, in which the baffle may be set for any desired pulp density discharge to obtain the most efficient operation of the classifier, and when once set will automatically maintain the pulp at the overflow at a predetermined density.

Another object of my invention is the provision of an automatic overflow control baffle for classifiers or other pulp separating tanks, which may be manually set or adjusted at will to automatically maintain its lower edge submerged to a predetermined density point within the pulp according to the density of the pulp at that point where the larger waste particles of less specific gravity would accumulate, whereby to insure constant separation of said larger waste

particles from the pulp with the smaller particles or fines so as to prevent to a greater extent than is usual the regrinding and resulting sliming of the material.

Still another object of the invention is the provision of pulp flow control means for the purpose above set forth which is simple in construction and which is automatically adjustable by variations in density of the pulp, whereby the pulp spilling over the tank weir will be substantially uniform specific gravity irrespective of the rate of speed at which the apparatus is operated, the inclination of the tank bottom, or the type of mechanical conveyor employed.

For a more complete understanding of the nature and objects of the invention, reference will now be had to the following detailed description, taken in connection with the accompanying drawings, wherein—

Figure 1 is a side elevational view of a wet material classifier showing the application of my invention in one embodiment thereof;

Fig. 2 is a perspective view of the automatic pulp flow control means, shown in Fig. 1;

Fig. 2A is a fragmental side elevation of a modified form of the structure of Fig. 2;

Fig. 3 is a fragmental top plan view of a modified form of the invention;

Fig. 4 is a slightly enlarged vertical section of the automatic baffle of Fig. 3 and disclosing in association therewith the supporting pulp of varying density from the top towards the bottom of the tank adjacent the back or overflow end thereof;

Fig. 5 is a view similar to Fig. 2 disclosing a modified form of automatically operable flow control baffle;

Fig. 6 is an isometric view of a portion of the baffle structure of Fig. 5 as observed from the front of the vertical plate member; and

Fig. 7 is a fragmental view partly in side elevation and partly in vertical section showing the application of the flow control means of Figs. 5 and 6.

Referring now in detail to the drawings, 10 designates an elongated tank having a bottom wall 11 (Fig. 4) which slopes downwardly towards the back or overflow end wall 12, and side walls 13 (Fig. 3) whose upper edges may also slope downwardly towards the back end 12. As shown in Fig. 1, the end wall 12 is closed except at the upper end or weir where the pulp overflows, as indicated at 14.

The material to be treated in a tank classifier such as is shown in Fig. 1, is usually first ground in a ball mill and mixed with water and delivered as pulp through a launder 15 to the tank 10 wherein the pulp is constantly maintained at the level l, l' . For this purpose the back end wall 12 is provided with the overflow lip 16 which discharges into the launder 17 as finished material.

A rake or other suitable mechanical conveyor 18 is usually provided at the bottom of the tank and this conveyor is operated constantly for the purpose of elevating and discharging the heavier particles which have settled through the pulp to the bottom of the tank by specific gravity, into a launder 19. The launder, as shown, is usually mounted at the front end of the tank and serves to return such recovered particles as are elevated by the mechanical conveyor 18, to the ball mill (not shown) for regrinding. The pulp thus produced by grinding and/or regrinding operations consists of particles of variable sizes, while gen-

erally the smaller particles will remain longest in suspension in the tank so as to be discharged over the lip 16 of the weir, this is not always so since these smaller particles may vary substantially in density or specific gravity. Thus, to produce the maximum separation and discharge of the larger particles of waste material with the smaller sized particles of the heavier and more valuable material for regrinding is provided by my invention now to be described in detail.

It is to be understood that the process is continuous and the essence of the present invention is the provision of an automatic control baffle means for the pulp flow in a settling tank whereby ground material of uniform density may be separated continuously from the pulp during operation of the device.

Such means in accordance with one embodiment thereof comprises a pair of arms 21 having triangular grooves 21^a in their lower faces adjacent corresponding ends thereof for selective pivotal engagement with a pivot bar 22 suitably supported by the sides 13 of the tank. The opposite or forward ends of the arms support at right angles thereto a baffle plate 23 having secured to and along its lower edge a suitable buoyancy member 24 which, as indicated in Figs. 1 and 2, may advantageously consist of a bevelled sided wood or other buoyant bar 24 to which one or more flat wood strips 24^a may be added or taken from the bar to provide proper buoyancy of the baffle plate in the pulp P.

As indicated in Fig. 1, the baffle plate 23 is positioned in rearwardly spaced relation to the back end tank wall 12 with a substantial portion thereof extending into the pulp and thereby providing a passage through which the pulp of the predetermined density at the bottom of the buoyancy member will flow upwardly and spill over the weir at the discharge lip 16 and into the launder 17.

This adjustable, pivotally supported and pulp-buoyed baffle will automatically adjust itself, due to any changes of the density of the pulp so that pulp of a uniform density will at all times be discharged by the baffle over the lip 16.

In order to adjust the baffle plate to secure pulp of varying densities, a weight or weights of any suitable form may be provided between the pivot bar 22 and the plate 23, and may advantageously be in the form of a bar 25 frictionally slidable along the arms 21, as by means of springs 25^a secured to the ends of the bar and engaging the bottom faces of the arms.

A modified, and what may be a preferred form of buoyancy means is disclosed in Fig. 2A, wherein the baffle plate 23 is return-bent upon itself adjacent its lower edge with the bent-over portion arched outwardly from the body portion of the plate as at 23^a and with the edge of the bent-over portion secured, as by welding or otherwise, to the plate, thereby providing an air chamber to effect proper buoyancy of the baffle. The ends of this chamber are closed as indicated in Fig. 2A, which also depicts another form of buoyancy adjusting weight which may advantageously consist of a flange 23^b having apertures for selectively receiving a desired number of weights 26.

While the structure of Figs. 1, 2 and 2A are highly efficient in operation, other forms or modifications of the invention may fall within the range of the broader aspects of the invention, such for example, as exemplified in Figs. 3 and 4.

In these latter figures a lever bar or arm 27 is

pivoted on the side walls 13 of the tank intermediate its ends, as at 28. This lever bar is provided at its front end with a depending baffle plate 29 which extends into the pulp P and a buoyancy member 29^a is provided as in Fig. 2A.

As indicated in Fig. 4 the density of the pulp P gradually increases from the top level 1 to the bottom of the tank, and as the flow of the pulp is in the direction of the overflow lip 16, the density of the pulp spilling over the lip will always be that in the horizontal plane of the lower end of the baffle 29. With the pivoted lever arm 27 the baffle 29 will maintain a constant density in that portion of the pulp spilled over the lip 16, since it will rise or fall in accordance with increase or reduction of the density.

If increased or reduced density is desired in the pulp separated by the baffle and spilled over the lip 16 the lever arm 27 may be adjusted to rock on its pivot 28 as by means of one or more weights 29^b. These weights may be positioned as shown in solid or dotted lines in Fig. 3. Hence, if the lever arm is weighted at the left of the pivot 28 the baffle 29 will be raised with a corresponding reduction in specific gravity of the pulp body spilled over the lip 16, while if the lever arm is weighted at the right of the pivot 28, the baffle 29 will fall with a corresponding increase in the specific gravity of the pulp body spilled over the lip.

A further form of pulp flow control means takes the form illustrated in Figs. 5, 6 and 7. This embodiment of the invention comprises a pair of supporting arms 30 which are adapted for pivotal support adjacent their rear ends on a pivot bar 31 supported upon opposite side walls of the tank 10. The forward ends of the arms 30 are secured as by braces 32 to a cross bar 33 extending parallel with the supporting or pivot bar 31. Secured to the bar 33 at its upper edge as by securing devices 34 is a thin metallic plate or baffle 35. The lower edge of the plate 35 is secured to a plurality of parallel and laterally spaced buoyancy bars 36. In this form washers 37 are preferably employed to maintain the vertically extending bars 36 in parallel laterally spaced relation, and a plurality of bolts 38 extend through the plate 35, bars 36 and washers 37 for rigidly maintaining same in this position. The bars 36 and washers 37 may be hollow or constructed of wood and the upper sides of the bars are preferably bevelled, as indicated, to avoid loading as by collection of sand or other material thereon.

While but three spaced buoyancy bars 36 are shown in form, more or less may be employed as conditions may warrant. Furthermore, suitable weights 39, as indicated in Fig. 5 may be employed to adjust the operation of the baffle to vary the density of the pulp spilling over the lip 16.

In this latter form of pulp control means, as in the former, the arms 30 are relatively long, whereby the plate 35 will be maintained substantially vertical, since the amount of rise and fall is always substantially small.

As indicated in Fig. 5, the arms 30 may be provided with a plurality of cooperating pivot notches 40 for varying the depth of submersion of the bars 36 as well as its relation to the front wall 12 of the tank. An application of the structure of Figs. 5 and 6 to the pulp tank 10 is illustrated in Fig. 7, wherein it will be observed that the bars 36 are submerged in the pulp and at the desired level where they will automatically adjust

the baffle plate 35 in accordance with the density of the pulp at that point.

As in Figs. 5 and 6, the top bevelled walls of the bars 36 will preclude the collection of settling material thereon.

While I have disclosed several specific structural embodiments of my invention, it is to be particularly noted that the principle of operation is the same with each, that is, the automatic density control of the flow of pulp over the classifier spillway or lip 16 is predetermined and maintained, i. e. the specific gravity of the pulp spilling from the settling tank over the lip 16 is always equal to that at the bottom of the adjustable automatically operable baffle, and not equal to the density of the pulp on the surface.

It is to be understood that the specific embodiments of the invention disclosed are illustrative only and not restrictive, the scope of the invention being defined in the subjoined claims.

What is claimed is:

1. In a classifier comprising a settling receptacle to which ground material and water in the form of pulp is constantly delivered and from which the properly sized material is constantly removed, and an overflow over which the properly sized material constantly flows; the improvement which comprises an imperforate, freely movable baffle extending transversely across the receptacle from a point above to a point below the liquid level and adjacent the overflow from the receptacle, said baffle being mounted for free vertical movement in the receptacle, and means associated with the baffle and immersed in the material in the receptacle for automatically moving and supporting the baffle in accordance with changes in the density of the pulp in the receptacle as constantly delivered thereto for maintaining the pulp flowing over the lip at a constant density.

2. Flow control means for use with a classifier which includes an elongated tank through which a pulp consisting of ground material and water constantly flows, and a lip at one end of the tank over which the pulp flows at the level thereof in the tank; comprising an imperforate buoyant baffle for vertical disposition within the tank and extending throughout substantially the width thereof adjacent to but spaced from the overflow lip, the baffle being free to move vertically within the tank and of a weight to extend pivotally into the pulp and to be buoyed up thereby according to the density thereof at the lower edge of the baffle, whereby the pulp flowing over the lip will be of constant density and equal to that of the pulp passing beneath the baffle.

3. Flow control means according to claim 2 wherein said baffle is supported by one end of a lever arm, means for pivotally supporting the lever arm on the tank, and weight means associated with the floating baffle for varying the depth to which the baffle is submerged in the pulp at any density thereof.

4. Flow control means according to claim 2, wherein said baffle includes a buoyancy member for submersion in the pulp, a vertical plate supporting said member at the lower edge thereof, lever arms connected at corresponding ends thereof to the plate, and means for pivotally supporting the arms adjacent the other ends on the tank.

5. In combination with the settling tank of a classifier having at one end thereof a lip over which flows a constantly moving pulp consisting of ground ore and water, means movably supported by the tank and having a part providing a

floating imperforate baffle extending across the tank to provide a flow restricting baffle adjacent said lip and extending partially into the pulp, said part being buoyed up by the specific gravity of the pulp and being thereby automatically adjustable to provide a constant density of the pulp flowing over said lip.

6. The structure according to claim 5, wherein said means comprises a lever arm pivotally supported intermediate its ends on the side walls of the tank, wherein said part comprises a vertically disposed floating baffle supported by one end of the lever arm and extending throughout substantially the width of the tank.

7. In combination with the settling tank of a classifier through which constantly flows a pulp consisting of ground ore and water and which pulp flows over a lip at one end of the tank, means for providing a constant density in the pulp flowing over the lip comprising a vertically disposed floating imperforate baffle extending throughout substantially the width of the tank and in spaced relation to the lip, said baffle having a float at its lower edge disposed for submergence in the pulp and being free to be buoyed up to extend a material distance above the level of the pulp thereby, the pulp flowing from beneath the lower submerged edge of the baffle, upward between same and the adjacent end of the tank and thence over the over-flow lip, whereby the over-flow pulp is automatically maintained at a constant density due to the depth to which the baffle will sink or raise as specific gravity of the pulp varies.

8. The structure according to claim 7, together with means for varying the extent of submergence of the floating baffle in the pulp for correspondingly varying the density of the pulp flowing over the lip.

9. The structure according to claim 7, wherein said floating baffle is supported by one end of a lever arm pivotally supported intermediate its ends on said tank.

10. The structure according to claim 7 wherein said baffle is supported by corresponding ends of a pair of laterally spaced lever arms having pivotal support adjacent their other ends on the tank, and means for varying the depth of submergence of the floating baffle in the pulp.

11. In a classifier comprising an elongated set-

ting tank having side walls, a downwardly inclined bottom wall and a back wall, means for delivering ground ore and water into the said tank for providing a pulp, the back wall having an overflow lip for recovering the properly sized ore particles of the pulp flowing thereover, the improvement comprising a pair of lever arms pivotally supported adjacent their rear ends on said side walls, and a vertically disposed floating imperforate baffle carried by the forward ends of the arms and extending substantially the width of the tank in spaced relation to said back wall, the lower edge of the baffle including a float extending into the pulp from a point above the pulp level and being buoyed thereby about said pivotal support whereby the baffle rises or falls in accordance with the density of the pulp for maintaining a constant density of the pulp flowing therebeneath and over said lip.

12. The structure according to claim 11 together with means for increasing or diminishing the extent of submergence of the floating baffle with a corresponding change in the density of the pulp flowing over the lip.

13. The structure according to claim 11 wherein in said floating baffle comprises a thin metallic plate and the float comprises a plurality of parallel spaced buoyancy bars secured to the lower edge of the plate, the upper edges of said bars being bevelled to prevent accumulation of material thereon.

14. The structure according to claim 11 wherein in said floating baffle comprises a thin metallic plate and the float being at the lower edge of the plate and having an upper wall at an acute angle to said plate.

15. The structure according to claim 11 wherein in said floating baffle comprises a thin metallic plate having a lower edge portion thereof bent upon the body thereof and defining with the body of the plate an air chamber whose opposite ends are closed.

16. The structure according to claim 11 wherein in said floating baffle comprises a thin metallic plate having a lower edge portion thereof bent upon the body thereof and defining with the body of the plate an air chamber whose opposite ends are closed, and the upper wall of the air chamber being at an acute angle to the plate.
